UNITED STATES PATENT OFFICE.

DAVID BOYD, OF DAMARISCOTTA MILLS, MAINE.

ICE-SCRAPER.

SPECIFICATION forming part of Letters Patent No. 310,176, dated January 6, 1885.

Application filed September 2, 1884. (No model.)

To all whom it may concern:

Be it known that I, DAVID BOYD, a citizen of the United States, residing at Damariscotta Mills, in the county of Lincoln and State of Maine, have invented a new and useful Improvement in Ice-Scrapers, of which the following is a specification, reference being had to the accompanying drawings.

My invention relates to ice-scrapers; and it consists in the construction and novel arrangement of the parts, as will be hereinafter fully described, and particularly pointed out in the claims.

In the drawings, Figure 1 is a view in perspective of my improved ice-scraper. Fig. 2 is a side elevation showing the scraper in position for dumping its load, and Fig. 3 is a rear elevation.

Referring by letter to the accompanying drawings, A A designate the sled-runners, which are provided with metal shoes secured to their inner faces, as shown, and are connected by a bar, B, to which the thills C are attached by a rod, D, passed through the thill-eyes E. The sled-runners form the ends of the scraper, and are strengthened by brace-rods F, extending from the under face of the connecting-bar B to the inner faces of the runners A A. The body G of the scraper is of wood, and is hinged by angle-irons H to the upper rear portions of the runners A A. The front of the scraper, at its lower edge, is faced with metal I, in order to prolong its usefulness by preventing too rapid wear. Cleats J are secured to the body G of the scraper, near each end, and these cleats J J come just inside of the runners when the body of the scraper is in the position for scraping. To the rear face of the scraper are pivoted two levers, K and K', their outer ends projecting slightly beyond the outer faces of the runners A A. The inner ends of the levers K and K' are slotted, and are connected to a wooden bar, L, by bolts L', passed through the ends of the wooden bar and through the slots in the inner ends of the levers. The outer ends of the levers K and K' are reduced in size, and these

reduced ends pass through holes M in the rear ends of the catch-levers N N', fulcrumed to the ends of the scraper or runners A A. The catch-levers N N' have hooks O at their forward ends, which point downwardly, and when said hooks O engage studs P, projecting outwardly from the runners A A, the scraper is locked in the working position. When the scraper has become filled with snow and the operator desires to dump the load, he simply lifts on the wooden bar L, which causes the levers K and K' to operate the catch-levers N N', and releases the hooks O from the studs P, and permits the scraper to turn over far enough to dump the load of snow, after which the operator rights the scraper and proceeds as before, a handle, V, being provided for righting the scraper.

Having thus fully described my invention, what I claim as new, and desire to secure by Letters Patent of the United States, is—

1. The combination, with the connected runners having metal shoes secured to their inner faces, and keeper-studs P, projecting from their outer faces, of the scraper hinged to the runners by angle-irons provided with pivoted catch-levers N N', the slotted levers fulcrumed to the back of the scraper, and the wooden connecting-bar connected to the inner ends of the slotted levers by bolts and nuts, substantially as specified.

2. The combination, with the connected runners having thills coupled to the connecting-bar, of the scraper, having the face-plate I, the angle-irons pivoted to the runners and secured to the scraper, the pivoted catch-levers, and the pivoted slotted levers, and the wooden connecting-bar, substantially as specified.

In testimony that I claim the foregoing as my own I have hereto affixed my signature in presence of two witnesses.

DAVID BOYD.
